SAFETY MILK BOTTLE CONTAINER

William Harold Van Buskirk, Vancouver, British Columbia, Canada, assignor of one-half to Oliver Beaulieu, Vancouver, British Columbia, Canada

Application January 14, 1935, Serial No. 1,815

2 Claims. (Cl. 232—42)

My invention relates to holders for milk bottles, especially adapted to household service and it particularly has for an object to provide a sanitary, safe bottle container of a very simple and inexpensive construction, one which can be sold to the customer at a low price or even given away by milk dealers to their customers if desired.

A further object is to provide a milk bottle holder in the form of a box or housing rigidly supported on the door jamb or frame and so constructed that it cannot be opened from the outside save by means of an especially constructed "key".

15 A further object is to provide a milk bottle holder of the character above referred to in which provision is made to hold a bottle entirely enclosed in the box or receptacle and to provide an auxiliary holder for a second bottle to be suspended beneath the box or receptacle and held against removal when the box is locked.

20 Another object is to provide a milk bottle holder of the above indicated character in which the lock construction is such that it cannot be picked.

25 Other objects will in part be obvious and in part be pointed out hereinafter.

To the attainment of the aforesaid objects and ends the invention still further resides in the novel details of construction, combination and arrangement of parts, all of which will be first fully described in the following detailed description and then be particularly pointed out in the appended claims, reference being had to the drawing, in which:—

35 Figure 1 is a perspective view of a doorway with my invention in place.

Figure 2 is an enlarged detail perspective view of a portion of the same, showing the box or container open for the insertion of the milk bottles in the box and auxiliary holder respectively.

40 Figure 3 is a horizontal section on the line 3—3 of Figure 2.

Figure 4 is an enlarged detail sectional view of the lock.

45 Figure 5 is a detail elevation and part section of the "key" device for releasing the bolt of the lock.

In the drawing, in which like numerals and letters of reference indicate like parts in all the figures, 1 represents the outer face of a door frame against the side of which adjacent the door my present invention is designed to be mounted. The box or container is preferably made of sheet metal and consists of side walls 2, top 3, bottom 4 and front wall 5, the major por-

tion of the rear of the box being an open structure, there being a shallow back wall 6 provided with a transverse recess or depression 7 extending across the width of the box, one side wall being cut away, as at 8, in register with the recess 7 for the purpose of permitting the latch tongue 23, hereinafter again referred to, to pass into the recess 7 and cooperate with the end 15 of the latch bolt 13.

Extending from the front wall to the back wall 10 of the container is the casing 9 of the latch device. This casing comprises a tube 9, the ends of which are welded or otherwise secured to the front and back walls 5 and 6 of the box, the said walls being apertured in alignment with the interior of the tube 9. As best shown in Figure 4, the tube 9 has indentations 10 which serve as spring stops, and it contains two springs 11 and 18, respectively, separated by the stops 10.

Within the tube 9 is a ring 12 against which one end of the spring 11 presses. When no "key" is in place the ring 12 is stopped by engagement with the front wall 5, the hole 5x of which is of slightly less diameter than the internal diameter of the tube 9 to serve as a stop. The hole 5x, however, is of sufficient diameter to permit the insertion of the "key" 27, hereinafter again referred to. Slidable within the tube 9 is the latch bolt 13, the bolt having a collar 14 against which one end of the spring 18 presses. The latch bolt 13 has an extension 15 that passes through a hole 6x in the rear wall 6 and projects into the transverse recess 7 in order to cooperate with the tongue 23. The latch bolt 13 has a neck 16 and a tapered head 17. The diameter of the head 17 does not exceed that of the internal diameter of the ring 12.

19 designates the supporting plate which has a flange 19x to overlie the adjacent wall of the container when the container is in the closed or locked position. The plate 19 is provided with keyhole slots 20 extended in an inclined position so as to cooperate with the face of the door 33 to hold the container on the door frame. The slots 20 also cooperate with the screws 21 by means of 45 which the plate 19 is held against the side face of the door frame 1, as best shown in Figure 2.

23 is the latching tongue which is projected from the face of the plate 19 adjacent the door. The tongue 23 is of a somewhat resilient nature 50 and has a hole 22 for the reception of the latching end, 15, of the latch bolt 13 when the box is swung inwardly to the closed position.

24 are hinges, which hinge the box to the plate 19, and 25 is a spring clip, preferably stamped 55

from the side 2 which has the cut away portion 8 and which clip is used to hold milk tickets, memoranda, etc.

26 designates the auxiliary bottle receiver 5 which is composed of a hanger in the form of a U-shaped member, closed at the outer end by a permanent wall 26x and at the inner end closed by the door 33. Thus it will be seen that when the box is in the closed position the door 33 10 will serve as a closure for the back wall of the box or receptacle and also for the auxiliary receiver.

The "key" by which the box may be unlocked 15 consists of a tube 27 having a finger button 28 at one end, the tube and button slidably receiving a rod 29, one end of which is split at 20 to constitute resilient tongs 30. A spring 32 is carried on the rod 29, and at the outer end the rod is provided with a thumb button 31. The spring 20 32 serves to push the tube 27 over the split end of the tongs 30 to hold the same together retracted within the tube 27. It is to be understood that the rod 29 adjacent the slotted end 30 is of tubular form. The free ends of the tongs 30 are slightly 25 inwardly bent to fit over the head 17 of the latch bolt.

In order to unlock the box the "key" is inserted 30 through the opening 5x. As the "key" is inserted through the opening 5x the end of the tube 27 engages the ring 12 and pushes it inwardly. At the same time the operator draws the members 28 and 31 together to allow the tongs 30 to split and pass over the head 17. The tube 27, as the operator releases it, causes the tongs to grasp 35 the head 17. This grasping action is effected by the spring 32 pressing against the button 28 to force the tube 27 over the split ends. The "key" now having been secured in grasping position to the head 17, the operator simply pulls on the head 40 31, which withdraws the end 15 of the bolt and releases the box from the latching tongue 23 so that the box may be swung to the open position for the insertion or removal of the milk bottles.

45 The flange 19x, hereinbefore referred to, allows for the thickness of the hinges and screw heads, etc., and prevents a space being left between the hinge side of the box and the plate 19 when the box is swung to the closed position, thus making it impossible to get an instrument between the box and the plate for the purpose of bending the latching tongue away from the latch bolt.

In order that the operator may not inadvertently leave the "key" in the tube 9 after he has released it from the head 17, I have provided the spring 11 and collar 12, hereinbefore referred to. As soon as the operator releases the tongs 5 10 by pulling back on the button 29, while holding the button 31 against movement, the spring 11 will tend to force the "key" out. Should the operator let go of the "key" it will be ejected by the action of the spring 11.

10 From the foregoing description, taken in connection with the accompanying drawing, it is thought that the complete construction, operation and advantages of my invention will be clear to those skilled in the art.

15 What I claim is:

1. In a milk bottle holder, a support, a bottle holding box hinged thereto and having an open face, means cooperative with said support to close said face, a device for locking the box in the closed 20 position, said device comprising a latching tongue carried by the support and a locking device carried by the box, the locking device comprising a latch bolt, a tubular bolt receiver and container, spring means in the bolt receiver and container 25 for projecting an end of the bolt to engage said latching tongue, said bolt having a head within the receiver for receiving a gripping means insertable into the tubular receiver through the front end of the same.

2. In a milk bottle holder, a support, a bottle holding box hinged thereto and having an open face, means cooperative with said support to close said face, a device for locking the box in the closed position, said device comprising a latching tongue 35 carried by the support and a locking device carried by the box, the locking device comprising a latch bolt, a tubular bolt receiver and container, spring means in the bolt receiver and container for projecting an end of the bolt to engage said 40 latching tongue, said bolt having a head within the receiver for receiving a gripping means insertable into the tubular receiver through the front end of the same, a guard collar in the tubular receiver and spring means normally holding 45 said collar beyond the end of the bolt, the guard collar being adapted to be pushed out of the way by the gripping means to enable the gripping means to pass over the bolt head into a position to grip the same.
